(57) **CLAIM**

We claim the ornamental design for auxiliary headlamp for motor vehicles, as shown and described.

DESCRIPTION

FIG. 1 is a front elevation view of an auxiliary headlamp for motor vehicles showing our new design;
FIG. 2 is a top plan view thereof;
FIG. 3 is a bottom plan view thereof;
FIG. 4 is a right elevation view thereof;
FIG. 5 is a left elevation view thereof;
FIG. 6 is a back elevation view thereof; and,
FIG. 7 is a front-right perspective view thereof.
Structure that is not part of the claimed design is shown in broken lines in the figures.
